UNITED STATES PATENT OFFICE.

ERNEST F. BARTH, OF RIDGWAY, PENNSYLVANIA.

WINDOW.

Application filed February 20, 1925. Serial No. 10,632.

To all whom it may concern:

Be it known that I, ERNEST F. BARTH, a citizen of the United States, residing at Ridgway, in the county of Elk and State of Pennsylvania, have invented new and useful Improvements in Windows, of which the following is a specification.

This invention relates to window structures, wherein the upper and lower sashes are capable of sliding movement, and also mounted to be swung inwardly upon pivots to facilitate cleaning of the windows, means being employed for holding the sashes against such pivotal movement under normal conditions.

More specifically stated the invention comprehends the provision of an upper and lower window sash, each of which includes an auxiliary section in which the pane of glass is arranged, the auxiliary section being mounted for pivotal movement, so that it can be swung inwardly for the purpose of cleaning the pane, together with means for normally holding the auxiliary section fixed with relation to the sash proper.

Another object of the invention resides in a construction which provides a water proof connection between the auxiliary section and the sash proper.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a front elevation of a window constructed in accordance with the present invention.

Figure 2 is a vertical sectional view therethrough.

Figure 3 is a fragmentary perspective view of the upper sash showing the auxiliary section swung inwardly.

Figure 4 is a similar view of the lower sash showing the auxiliary section thereof swung inwardly.

Figure 5 is a sectional view on line 5—5 of Figure 1.

Referring to the drawings in detail, A indicates a window frame of any well known construction in which the upper and lower

sashes are mounted for vertical sliding movement, so that the windows can be raised and lowered in the ordinary manner.

In accordance with the present invention, the upper sash indicated at 10 has its inner edge bevelled to correspond with the bevelled outer edge of the auxiliary sash section 11 which is pivoted as at 12 between the opposed side members of the sash 10 as clearly shown in Figure 1. The auxiliary section 11 supports the pane of glass 13, and is of a size to wholly lie within the confines of the sash 10, when in its normal position as shown in Figures 1 and 2. The upper cross member 14 of the auxiliary section has associated therewith one or more pins 15 which are adapted to be threaded into openings in the adjacent rail of the sash 10 as clearly indicated in Figure 2, in order to hold the auxiliary section fixed with relation to the sash as will be readily understood. When it is desired to clean the glass panel 13 of the upper sash it is only necessary to separate the pins 15 from the sash 10, thereby freeing the auxiliary section 11 so that it can be swung inwardly to the position shown in Figure 3. When in this position both sides of the glass panel can be easily and conveniently cleaned, and the auxiliary section subsequently moved to its normal position.

The lower sash is indicated at 16, and is also provided with an auxiliary section indicated at 17, which section supports the glass panel 18 in the usual manner. The auxiliary section 17 is pivoted or hinged as at 19 to one side member of the sash 16, so that the auxiliary section can be swung inwardly to the position shown in Figure 4 when it is desired to clean the panel 18. For the purpose of holding the auxiliary section 17 fixed with relation to the sash 16, I preferably employ a pair of pins 20 which are adapted to be threaded through openings in the sides of the auxiliary section, and passed through openings in the adjacent sides of the sash 16 to cooperate with rods 21 which are utilized for a purpose to be presently described. However each rod is formed with a groove to receive the pin 21 as shown in Figure 5, and the auxiliary section 17 cannot be moved with relation to the sash 16 until after the pins 20 have been separated from the rods 21. This is caused by the fact that the lower rail of the auxiliary section is bevelled as at 22 and normally engages the bevelled surface

23 of the adjacent rail of the sash 16, and these bevelled surfaces prevent the auxiliary section from being moved inwardly when the parts are arranged as shown in 5 Figure 2. However the lower rail of the section 16 is capable of vertical movement toward and away from the adjacent rail of the auxiliary section, and when the lower rail of the sash is dropped to the position 10 shown in Figure 4, it is wholly separated from the auxiliary section so that the latter is free to be swung inwardly for the purpose stated. This lower rail or sash 16 is supported by the rods 20 above referred 15 to, and these rods slide in openings in the sides of the sash as indicated by dotted lines in Figure 4, each rod having a groove 24. When the said rail of the sash is in a normal position, the grooves 24 are arranged 20 to receive the pins 20 in the manner above described, thus allowing the lower rail of the sash in contacting engagement with the adjacent rail of the auxiliary section as illustrated in Figure 2. Carried by the lower 25 rail of the sash is a flange 25 which bridges the joint or coupling between the adjacent rails of the sash 16 in the auxiliary section 17 when the parts are arranged as shown in Figure 2, this flange 25 together with the bevelled surfaces 22 and 23 preventing rain water or the like from finding its way between said parts. The invention is very simple in construction and can be easily manipulated for the purpose intended.

30 While it is believed that from the foregoing description, the nature and advantages of the invention will be readily apparent, I desire to have it understood that I do not limit myself to what is herein shown 40 and described, and that such changes may

be resorted to when desired as fall within the scope of what is claimed.

Having thus described the invention, I claim:

1. In a window structure, a frame, upper 45 and lower sliding sashes, said lower sash including an auxiliary section pivoted on the sash to swing inwardly therefrom, the adjacent lower rails of said sash and auxiliary section having bevelled surfaces normally contacting, said lower rails of the sash being capable of movement toward and away from the adjacent rail of said auxiliary section, and adapted to be spaced therefrom to allow the section to be swung 50 inwardly, and means for normally holding the rail of the sash elevated and the said bevelled surfaces in contacting engagement.

2. A window sash including an auxiliary section pivoted on the sash and capable of being swung inwardly therefrom, the lower rail of said sash and the adjacent rail of said section having bevelled surfaces normally arranged in contacting engagement, said rail of the sash being capable of movement toward and away from the adjacent rail of the auxiliary section, rods rising from the rail of said sash and slidably received by the adjacent side members thereof, means carried by the auxiliary section and cooperating with said rods to normally hold the lower rail of the sash elevated and said bevelled surfaces in engagement with each other, and a flange rising from said rail of the sash and bridging the joint between said rails for the purpose specified.

60 In testimony whereof I affix my signature.

65 ERNEST F. BARTH.
